US0D1087483S

(12) United States Design Patent (10) Patent No.: US D1,087,483 S
(45) Date of Patent: * Aug. 5, 2025

(54) CAT BED

(71) Applicant: Ziel Home Furnishing Technology Co., Ltd., Henan (CN)

(72) Inventor: Chuan Song, Henan (CN)

(73) Assignee: Ziel Home Furnishing Technology Co., Ltd., Zhengzhou (CN)

() Term: 15 Years

(21) Appl. No.: 29/915,862

(22) Filed: Nov. 6, 2023

(30) Foreign Application Priority Data

Oct. 25, 2023 (CN) 202330691981.9

(51) LOC (15) Cl. 30-06

(52) U.S. Cl.

USPC D30/118

(58) Field of Classification Search

USPC D30/108, 118, 119; D6/331, 390, 391,
D6/392

CPC A01K 1/0353; A01K 1/0272

(57) CLAIM

The ornamental design for a cat bed, as shown and described.

DESCRIPTION

FIG. 1 is a front view of a cat bed showing my new design; FIG. 2 is a rear view of the cat bed of FIG. 1; FIG. 3 is a left side view of the cat bed of FIG. 1; FIG. 4 is a right side view of the cat bed of FIG. 1; FIG. 5 is a top view of the cat bed of FIG. 1; FIG. 6 is a bottom view of the cat bed of FIG. 1; FIG. 7 is a perspective view of the cat bed of FIG. 1; and, FIG. 8 is an enlarged view portion 8 in FIG. 7. The broken lines in FIGS. 7 and 8 illustrate a boundary and cut line of the enlarged view in FIG. 8 and form no part of the claimed design.

1 Claim, 8 Drawing Sheets
